UNITED STATES PATENT OFFICE.

THOMAS H. DELANEY, OF NORWICH, CONNECTICUT.

HYDROCARBON-BURNER.

SPECIFICATION forming part of Letters Patent No. 757,027, dated April 12, 1904.

Application filed March 28, 1903. Serial No. 149,958. (No model.)

To all whom it may concern:

Be it known that I, THOMAS H. DELANEY, a citizen of the United States, residing at Norwich, in the county of New London and State of Connecticut, have invented a new and useful Improvement in Hydrocarbon-Burners, of which the following is a specification, reference being had to the accompanying sheet of drawings.

10 My object is to provide a convenient and economical form of hydrocarbon-burner for use in stoves, ranges, and house-heating apparatus, and particularly to so improve such burners that perfect combustion shall be assured, thus overcoming the objectionable smoke and odor now so common in this class of burners.

15 In order to explain my invention clearly, I have provided the annexed drawings, in which—

20 Figure 1 is a side elevation of a burner embodying my improvements, and Fig. 2 is a plan view of the same. My improved burner is built up of three superimposed sections or parts, and in Fig. 3 I have shown the burner with the cover-plate removed. In Fig. 4 I have shown it with the cover-plate and retort-casting removed, thus disclosing a plan view of the pan. Fig. 5 is a cross-sectional view 25 of the complete burner, taken on line 5 5 of Fig. 2; and Fig. 6 is a similar view taken on line 6 6 of said Fig. 2.

25 In the drawings the letter *a* indicates the base-section, which is a pan, *b* the intermediate section or retort-casting, and *c* the top section or cover-plate which fits over the retort-casting, these sections being preferably of cast metal.

30 The base-section *a* is formed substantially as a rectangular pan with upright corner-posts *a'*, upon which the intermediate section *b* rests, the posts being of such height that a considerable open space is provided between the base and intermediate sections, through which space the flames may pass outward and contact with the adjacent walls of the stove or range when the burner is in use. The bottom 35 of the intermediate section is set in somewhat, as seen in Fig. 1, to receive the described corner-posts *a'*. The upper portion of section *b* is

formed with a longitudinal channel or recess *b'*, that is located near one side of said section and serves as a conduit through which a plentiful supply of fresh air is introduced into the burner, as I will explain more fully later. The 40 channel *b'* is connected with the outside atmosphere by an inlet-pipe *d*. The intermediate section *b* is also formed with a central transverse chamber *b*², into the lower part of which an oil-supply pipe *e* leads, as seen in Fig. 5, and in the pipe *e* at some convenient point outside the burner is a valve *e'*, by means of which the flow of oil into the chamber *b*² may be controlled. Connected with the central chamber, *b*² are oppositely-extending channels *b*³, that 45 connect with like channels *b*⁴ at the ends of the said section *b*, as is best seen in Fig. 3. On the opposite sides of the central chamber *b*² (within the inclosure formed by said chamber and the channels *b'* *b*³ *b*⁴) are openings 50 *b*⁵ *b*⁶, and in the center of each of said openings is a vertical pipe-section *g*, whose lower ends are open, as is clearly seen in Figs. 5 and 6. These pipes *g* form mixing-tubes. A short pipe *g'* connects each of said vertical pipes 55 with the described air-conduit *b'*, and the upper end of pipe *g* is connected by a pipe *g*² with the end channel *b*⁴ in such manner that vaporized oil may pass from the said channels *b*⁴ to and through the vertical pipes *g*. Each 60 pipe *g*² is provided at the point where it discharges into the vertical pipe *g* with a restricted opening in the form of a plug *g*³, having a very small central perforation.

65 The top section *c* and the intermediate section *b* are secured together by a number of bolts or screws *h*.

70 When my described burner is in service, the pipe *e* is connected with a suitable reservoir of oil, (preferably crude or refined petroleum.) 75 When it is desired to start a fire, a piece of paper or oil-saturated rag is first placed underneath the central chamber *b*² and lighted. This immediately warms up the bottom and side walls of said chamber *b*, so that when a 80 small jet of oil is introduced through the inlet-pipe *e* said oil in seeking to spread over the bottom of chamber *b*² is vaporized and in seeking to escape passes through the channels *b*³ into the end channels *b*⁴ and thence escapes 85

through the pipes g^2 into the vertical pipes g . The rapid accumulation of vaporized oil in the channels b^2 , b^3 , and b^4 creates a considerable pressure, so that said vapor is forced through 5 the small opening g^3 into the vertical pipe g , where it mingles with a jet of air introduced through the pipe g' , thus providing an inflammable gas that burns freely at the lower or discharge ends of the pipes g . These flames im- 10 ping on the bottom of the base-section a and spread in all directions, passing outward through the openings between sections a and b on all sides. The entire structure soon becomes cherry-red and radiates intense heat.

15 Each of the pipes g^2 includes a cut-off valve g^4 and preferably a screw-plug g^5 , through which the interior of the vertical pipes g may be reached and cleaned, if necessary. The cut-off valves g^4 provide convenient means for 20 shutting off, either wholly or partly, either of the burners, thus making it possible to shut off at will half of the oil consumption and to correspondingly modify the fire.

It will thus be seen that I provide a burner 25 in which the oily vapor and air are mingled before they are brought into contact with the flame instead of injecting or dropping the oil into a retort where it burns before being suitably mingled with air, as has sometimes been 30 done. My present arrangement, with means for controlling the inflow and mingling of the vapor and air, enables me to proportion and regulate the same so that perfect combustion is attained with the least possible use of oil.

35 Having thus described my invention, I claim—

1. In a hydrocarbon-burner three superimposed sections, a base-section or pan, corner-posts, an intermediate section or retort-casting 40 resting upon said corner-posts with an air-space therebetween, the bottom of the retort-casting being set in to receive said corner-posts, said retort-casting being formed with a central transverse chamber, oppositely-extending channels connecting with said central chamber and with like channels at the end of 45 said section.

2. A hydrocarbon-burner composed of three superimposed sections, a base-section or pan, 50 corner-posts, an intermediate section or retort-casting resting upon said corner-posts with an air-space therebetween, the bottom of the retort-section being set in to receive said corner-posts, said retort-casting being formed 55 with a central transverse chamber oppositely-extending channels connecting with said central chamber and with like channels at the end of said section, a cover-plate for said retort-casting, and mixing-tubes depending from the 60 cover-plate into the said retort-casting, and vapor-discharging pipes for discharging vapor into said mixing-tubes, said vapor-discharge pipes each being connected to the end channels of the retort-casting.

65 3. A hydrocarbon-burner composed of three

superimposed sections, a base-section or pan, corner-posts, an intermediate section or retort-casting resting upon said corner-posts with an air-space therebetween, a cover-plate for said retort-casting, and mixing-tubes depending 70 from the cover-plate into the retort-casting, and vapor-discharging pipes for discharging vapor into said mixing-tubes, the bottom of the retort-casting being set in to receive the corner-posts, said retort-casting being formed 75 with a central transverse chamber, oppositely-extending channels connecting with said central chamber and with the like channels at the end of said section, and a longitudinal channel for the introduction of fresh air. 80

4. A hydrocarbon - burner, composed of three superimposed sections, a base-section or pan, corner-posts, an intermediate section or retort-casting resting upon said corner-posts with an air-space therebetween, a cover-plate 85 for said retort-casting, mixing-tubes depending from the cover-plate into the retort-casting, vapor-discharge pipes for discharging vapor into said mixing-tubes, the bottom of the retort-casting being set in to receive said corner-posts, said retort-casting being formed with a central transverse chamber, oppositely-extending channels connecting with said central chamber and with like channels at the end of 90 said section, a connection between the mixing-tubes and a longitudinal air-channel for the introduction of fresh air, and an oil-supply pipe leading into the lower part of said central transverse chamber. 95

5. In a hydrocarbon-burner, in combination, 100 a base-section or pan, a retort casting or section mounted on said base-section and formed with central transverse chamber with openings on opposite sides of said chamber and channels at the ends of said section communicating with the oppositely-extending channels and an air-duct for introducing fresh air to the burner, downwardly-discharging burner-pipes located in said openings, pipe connections between the end channels and said pipes, 105 a connection between said duct and the vapor-discharge pipes, and an oil-supply pipe connected with the central transverse chamber of said retort-section. 110

6. A hydrocarbon - burner, comprising a 115 base-section or pan, a retort casting or section mounted on the base-section and formed with central transverse chamber with openings on opposite sides of said chamber, vertical pipes extending into said openings, a short pipe connecting each of said vertical pipes with the longitudinal channel for the introduction of fresh air to the burner, a cover-plate for the retort-casting, mixing-tubes depending from the said cover-plate into the retort-casting, 120 and vapor-discharge pipes for discharging vapor into the said depending tubes, which latter form mixing-tubes. 125

7. A hydrocarbon-burner comprising three 130 superimposed sections, a base-section or pan,

an intermediate section, and a retort casting or section, the latter being formed with a central transverse chamber, oppositely-extending channels connecting with said central chamber and with like channels at the end of said casting, a top section secured to the retort-casting, pipes connecting the end channels, plugs in said pipes, cut-off valves, vertical pipes extending into the retort-casting and 10 forming mixing-tubes, a longitudinal channel for the introduction of fresh air to the burner,

an oil-supply pipe leading into the lower part of the said central transverse chamber, and short pipes connecting the vertical pipes with the said longitudinal channel.

15

In testimony whereof I have signed my name to this specification in the presence of two subscribing witnesses.
